UNITED STATES PATENT OFFICE

PAUL SWITZENY, OF VIENNA, AUSTRIA

STAPLING DEVICE

Application filed May 8, 1930, Serial No. 450,852, and in Austria December 13, 1929.

This invention relates to improvements in hand stapling devices operating in known manner with staples or clips. In the known hand stapling devices, the device is charged by sliding the clips from the package onto the winged channel, which is to receive the clips. However this cannot be carried out with certainty, so that the clips often have to be applied one by one. If a staple got bent or squeezed or the like, all the clips had to be removed from the device by drawing or shaking off the same and the clips again had to be replaced one by one with a considerable loss of time. Further, in order not to unduly increase the entire length of the apparatus, the stroke of the spring for feeding the clips had to be limited, thereby restricting in the apparatus the number of clips (about 50 pieces) and this again called for a frequent charging.

20 The invention provides arrangement whereby the charging as well as the discharging of the clips can be carried out quickly and positively and at the same time the number of inserted clips is increased.

25 The present invention is illustrated by way of example on the accompanying sheets of drawings, in which:—

Fig. 1 is a side view,
Fig. 2 a plan view and
30 Fig. 3 a sectional view of the device, the section being taken on line A—B of Fig. 1.
Figs. 4 and 5 are perspective views of details.
Fig. 6 shows a particular construction of the bed plate, and
35 Fig. 7 the general view of the hand stapling device with this bed plate.
Fig. 8 shows in a plan view a modified construction of the bed plate, and
40 Fig. 9 illustrating the hand stapling device with this bed plate in the extended condition and partly in section.

The arrangement of the main parts of the hand stapling device deviates not essentially but only in operation from the known constructions and consists of the bed plate 1 which is connected by the hinge 2 to the lever piece 3, on the free end of which is guided the top die 4. In the known constructions the lever piece 3 is in the shape of a winged

channel member, onto which the clips are fed. According to the invention the clips 5 are charged onto a separate winged channel member 6, which can be pushed into spaced grooves of the lever piece 3, so that a squeezed or bent staple can be readily removed thereby if the whole winged channel member with the string of clips is moved backward out of the groove. In the particular construction according to the invention, the 55 channel member 6 is bent from a sheet metal plate to form a hollow body, which is somewhat resilient and provided with outward bent flanges at the edges of the base, and which is open at the bottom. The groove in the lever piece 3 is slightly tapered at the front, so that the inserted winged channel member has a firm seat. The member 6 has on the back an extension 8, which is stepped on all three sides, and on which is pushed the 60 U-shaped plate of the original style package, so that it is flush at all three sides with the member 6, and the clips can be applied without obstruction and safely onto the member 6. According to the invention, the pivot 2 is provided in order to secure the winged channel member in the correct position. For this purpose the flange 9 is cut and bent inward to form an eye 10 (or only to a semi-circular bearing or the like) through which the bolt 2 65 is pushed.

70 The arrangement for feeding the clips is constructed as shown in Fig. 5 and consists of a slide 11, which fits on the member 6 provided with flanges 12 at the front edge. 75 After the last clip has been used, the flanges rest against the die 13 and thus prevent the slide to pass under the said die. The spring loaded rod 14 is guided in a bearing 15 secured to the slide 11. The bearing 15 is arranged on the slide 11 so far back, that the front face of the slide actually pushes the last clip underneath the die 13. The flanges 12 are formed in such a way, that they allow the head of the spring loaded rod 14 to pass (Figs. 1 and 2). The rear end of the spring loaded rod 14 is in the shape of a handle and at the same time bent down. The member 6 is provided with two or more holes 16, 17, 80 85 90 95 100 into which the cranked part of the spring

loaded rod 14 can be placed according to requirement. The effect is that the whole feed length of the spring can be fully utilized a number of times and therefore more clips 5 can be placed onto the member 6. At first the spring loaded rod 14 is fixed in the hole 16 if the stapling device is fully charged. If a number of clips have been used, so that the spring is slack, the spring loaded rod will 10 be pushed forward thereby placing in tension the spring and its end is placed into the hole 17.

A spring 18 is arranged below the hinge and acts on the lever part 3 in such a way, 15 that the same usually is held in the open position and only is turned down by the pressure on the die when using the device.

The construction of the member 6 in the shape of a hollow body with eyes 10 allows 20 the hand stapling device, after removing bolt 2, to be used in connection with a special bed plate 19, which according to the invention is shaped like a ruler and preferably graduated and carries an arm 20, which allows the 25 paper to be pinned together to be pushed underneath, so that the sheet can be stitched also in the centre. The graduation of the ruler allows a uniform insertion of the sheets. The arm 20 to be screwed to the ruler is 30 punched out of a plate 21 and bent upward. Lugs 22 are formed by bending the free ends, the said lugs being provided with eyes for the bolt 2.

When using the device, the winged channel member 6 is pushed over the end of the arm 20 and fixed by inserting the bolt 2 into the eyes of lugs 22. The die 23 is fixed at a 35 suitable distance on the ruler.

In the stapling device above described the 40 bed plate, according to the length of the backward extending staple guide, is little turnable at most at about 90° , so that the hand stapling device cannot be used at an object where the bed plate can not pass underneath, 45 for instance nailing at boxes or walls and so forth, as the staple mechanism cannot be placed flat on the object to be treated in view of the obstruction by the bed plate.

In the construction shown in Figs. 8 and 50 9 this drawback is avoided in that the rearwardly extending part of the hinged bed plate is recessed at least over the width of the staple guide, to allow a turning of the bed plate of substantially 180° with respect to 55 the staple guide, that is to say that the staple mechanism and the outwardly turned bed plate come to lie substantially in a line.

The bed plate 1 is pivoted to the staple mechanism by means of the hinge. The bed plate 1 is provided with an opening or recess 60 24, which extends from the hinge to the rear end to allow a swinging of the bed plate 1 with respect to the staple mechanism at 180° into the position shown in Fig. 9. Now the 65 staple mechanism can be placed flat in the

middle of the box-lid or the like, so that it is possible to fix the lid on the box 26 or strengthening strips to the lid in a most simple manner, without interfering with the bed plate.

To allow for a staple mechanism with long 70 backward extending staple guide 3', the bed plate is also provided with an opening 25 in front of hinge 2, in which the projecting end of the staple guide 3' lies, if the bed plate is 75 turned out that is in the position shown in Fig. 9.

In view of the particular arrangement of 80 the bed plate it is possible to apply the hand stapling device to walls or other large surfaces without removing the bed plate.

I claim:—

1. A stapling device comprising a lever piece, a pivot pin therefor, a carrying and guiding member for staples bent out of sheet metal and adapted to slide in the lever piece, said carrying and guiding member being adapted to yieldingly slide in tapered grooves and being secured by the pivot pin by means of a lug carried by said member, the upper portion of the member being provided with spaced openings, and a spring feed device for staples including a guide rod adjustably engageable in the opening of said member corresponding to the condition of the supply of 95 clips.

2. A stapling device as claimed in claim 1, characterized by the provision of a ruler-like graduated bed plate, and a tongue punched and bent out of said bed plate, said 100 tongue permitting the paper which is to be fastened to be pushed underneath and having on its free end a bearing eye for the pivot pin.

In testimony whereof I affix my signature.

PAUL SWITZENY.
